NEEDLE BAR

Anton Loimann, Chemnitz, Germany

Application August 21, 1936, Serial No. 97,293
In Germany August 23, 1935

1 Claim. (Cl. 66—114)

This invention relates to improvements in needle bars for flat hosiery machines, more especially for common hosiery frames, the needle bar being shaped to form a kind of girder or beam stiffened by ribs.

The object of the present invention is to reduce the weight of the needle bars more than possible with the old needle bars of this kind thus diminishing the motive power required for moving the needle bars and keeping the machine even when running at full speed free from disturbing vibrations. This object is attained by shaping the needle bar proper to form a box-shaped girder provided with ribs arranged in the interior of the box so as to form a lattice work. Furthermore at the points of intersection of the ribs holes are provided for letting the screw bolts belonging to the covers pass through, and at the underside of the box-shaped girder the bearing eyes are attached by casting in such a manner that at the points of junction the walls of the bearing eyes have approximately the same thickness as the walls of the box-shaped girder. When such needle bar is made of a light-metal alloy as in itself is usual in the art it is considerably lighter than a common needle bar. Regarding the fact that the needle bars in working a flat hosiery frame are moved in horizontal and vertical direction by jerks, this involves considerable saving of motive power and essentially diminishes the risk of the vibrations of the machine increasing to an annoying extent. Therefore a machine provided with needle bars according to the present invention may be run with higher speed than possible with the old needle bars under similar conditions.

The invention is illustrated by way of example in the annexed drawing of which

Fig. 1 is a front view and
Fig. 2 is a side view of a needle bar constructed according to the present invention.

The needle bar consists of a box-shaped hollow body formed by a front wall 1, the upper and the lower longitudinal walls 2 and 3 respectively, and the side walls 4 and 5 respectively. In the horizontal middle-line of this box-shaped girder a plurality of fastening eyes 6 is provided through which the screw-bolts extend by which the covers 9 for fastening the needles are attached to the needle bar. A number of stiffening ribs 7 extend from each of the eyes 6 to the upper and lower walls 2 and 3.

Hereby the strength of flexure and torsion of the needle bar is considerably increased so that it becomes possible to reduce the thickness of the walls of the box-shaped girder correspondingly.

In order to journal the needle bar at the holding and driving levers all otherwise required connecting members are dispensed with and four bearing eyes 8, offset in pairs, are attached by casting to the underside of the wall 3 so that the thickness of the walls of the bearing eyes approximately equals that of the box-shaped girder. I have ascertained that this thickness is quite sufficient in spite of the stresses which may occur at the points of junction.

The needle bar is preferably made of aluminum or a light metal alloy.

I claim:—

A girder-like needle bar stiffened by ribs for flat hosiery machines, which needle bar forms a box-shaped girder and is stiffened at its inside by lattice work ribs, cavities being provided at the points of intersection of the said ribs, cavities for letting the screw bolts, belonging to the covers, pass through, and bearing eyes being attached by casting to the underside of the girder, the thickness of the walls of the bearing eyes approximating that of the girder walls.

ANTON LOIMANN.
